UNITED STATES PATENT OFFICE.

HENRY FREDERICK TYZACK, OF GATESHEAD, ENGLAND, ASSIGNOR OF TWO-THIRDS TO HENRY SHADFORTH SCOTT, OF GATESHEAD, ENGLAND, AND ISIDOR SUMMERFIELD, OF NEWCASTLE-UPON-TYNE, ENGLAND.

REVERSIBLE STEAM-TURBINE.

SPECIFICATION forming part of Letters Patent No. 712,424, dated October 28, 1902.

Application filed July 21, 1902. Serial No. 116,400. (No model.)

To all whom it may concern:

Be it known that I, HENRY FREDERICK TYZACK, a subject of the British King, and a resident of Gateshead, England, have invented 5 certain new and useful Improvements in the Construction of Reversible Steam-Turbines; and I do hereby declare the following to be a full, clear, and exact description of the invention, such as will enable others skilled in 10 the art to which it appertains to make and use the same.

The object of this invention is to produce a steam-turbine of improved construction which can be reversed in its rotation, so as to 15 operate in either direction, and having other novel features.

The accompanying two sheets of drawings illustrate such a reversible turbine according to my invention and generally as I propose to 20 carry it into practical application.

Figure 1, Sheet 1, is an end view of one of the revolving disks secured upon the shaft; and Fig. 1^a is a section through same. Fig. 2 is an end view of one of the stationary disks 25 which are inverted between the revolving disks, and Fig. 2^a is a section through one of these disks. Fig. 3 shows a portion of two revolving disks with one stationary disk between them, forming the outer circle and the 30 inner circle of disks in Figs. 1, 1^a, 2, and 2^a. Fig. 4 is an enlarged section of part of two revolving disks and one stationary disk, showing the method of providing lateral stiffness in the direction of the line of shaft. Figs. 5 35 and 6, Sheet 2, show an end view and elevation one-half in section; and Figs. 5^a and 5^b, details of the steam-ports on Figs. 5 and 6 by which reversing is effected. Fig. 7, Sheet 1, shows a modified construction of the vanes in 40 one or more of the revolving disks to control the admission of steam and increase its energy.

The same letters indicate the same parts in all the figures.

On Figs. 1 and 1^a, Sheet 1, c is the main shaft, to which are secured the revolving disks, in which are the outer circle of ports or passages A, into which the steam enters to 45 revolve the disks in one direction, and A' the

inner circle, into which steam enters to revolve 50 them in the reverse direction.

Fig. 3 shows the disposition of the propelling-vanes of these ports A A' relatively to the ports in the stationary disks B B'.

Figs. 2 and 2^a show an end view and sectional elevation of the stationary disks B B', showing outer and inner circles of ports, with their angled vanes.

Fig. 4 shows, enlarged, a portion of a pair of revolving disks A A', having between 60 them a stationary disk B B', the latter being prevented from turning in the case J by set-bolts Q. The revolving disks and the stationary disks half lap with each other all around by the flanges K, thereby having 65 great stability given to the former in driving the shaft. Steam is prevented passing between the disks by grooves P, in which are inserted packing-rings P', secured by spigots P². 70

Referring to Sheet 2, Fig. 5 shows an end view one-half each of the reversing-plate E and steam-nozzle plate F, and Fig. 6 an elevation, one-half in section, to illustrate the method of reversing the revolution of the 75 disks. J is the outer casing into the steam-chest R, of which the steam enters at D, and after being expanded through the series of revolving disks is exhausted to the condenser or atmosphere at I. The reversing is effected 80 by a plate E, in which are slots L, and this plate has upon it a portion of a toothed rim N, into which a toothed pinion N' on a spindle O engages, so that by a handle G the slots will open to steam by the ports M and the 85 ports A to revolve the disks and shaft in one direction, closing the passages to the other ports A' in the disks, and vice versa, according to the direction of revolution required.

Figs. 5^a and 5^b, Sheet 2, show the angled 90 ports in the plate F, Fig. 6.

Fig. 6 shows the casing tapering larger in diameter toward the exhaust end; but it may be made in steps, each parallel with the axis and with one or more disks on each step. 95 The number of expansions depends upon the number of revolving and stationary disks and upon what proportion of the circle the

"live" steam operates before escaping into the next disk.

Fig. 7, Sheet 1, shows an enlargement of the method we may adopt to cause the steam to exert its full work upon the vanes by making it enter in the direction of the arrow and impinge upon the vanes S with increased effect by passing the contracted spaces at X. This construction of reversible steam-turbine is adapted to act as a brake to retard and bring to rest when suddenly required the action when going ahead or astern, as in propelling a steamer, by turning the slotted plate E so as to change the operation of the steam from one set of the revolving disks to the other set, this action when going ahead causing the vessel to overrun the propeller, which will revolve in the opposite direction and be gradually revolved without shock to go astern.

What I claim is—

1. In a reversible turbine, the combination with a plurality of revolving disks provided with an inner and outer circle of oppositely-disposed steam passages or buckets, of stationary disks located between said revolving disks provided with ports adapted to aline with the steam-passages of said revolving disks, a steam-chest on one side of the turbine communicating directly with said steam-passages of said revolving disks, an inlet-pipe for said steam-chest, means located in said steam-chest for controlling the delivery of the operating fluid from said inlet-pipe to one or the other of said series of steam-passages, and an exhaust-pipe for the expanded steam.

2. In a reversible turbine, the combination with a plurality of revolving disks provided with an inner and outer circle of oppositely-disposed steam-passages having angular sur-

faces or vanes, of stationary disks located between said revolving disks and having an inner and outer circle of ports adapted to aline with said steam-passages, an inlet-pipe, an exhaust-pipe, and a slotted plate interposed between said inlet-pipe and said steam-passages for controlling the delivery of the operating fluid to the inner or outer series of steam-passages.

3. In a reversible turbine the combination with a plurality of revolving disks provided with an inner and outer circle of oppositely-disposed steam-passages having angular surfaces or vanes, the passages of one circle being alternately disposed relative to the passages of the other circle; of stationary disks located between revolving disks and having angular ports adapted to aline with, and open communication between the inner and outer circle of steam-passages of one revolving disk and the corresponding steam-passages of the next adjacent disk, a steam-chest, an inlet-pipe, an exhaust-pipe, a stationary plate in said chest adjacent the face of the inner revolving disk and having a double series of alternating ports adapted to aline with the steam-passages therein, a slotted plate engaging said stationary plate, and means for rotating said slotted plate for opening communication, through either series of said alternating ports, between said steam-chest and the corresponding steam-passages in said revolving disks.

In testimony whereof I affix my signature in the presence of two witnesses.

HENRY FREDERICK TYZACK.
